WOOD-SURFACING MACHINE

Application filed April 10, 1926. Serial No. 101,033.

This invention relates to apparatus for the surface smoothing or finishing of woodwork and the like by abrasion, such as by sandpapering. It has to do particularly with a machine specially qualified for bench work, although not limited for its utility to such employment.

The general object of the invention is the provision of an efficient surface finishing or abrading machine of very compact construction and light weight, whereby it is specially qualified for employment as a hand manipulated bench tool susceptible of use by a workman with accuracy and without inconvenient physical exertion. The attainment of this object imposes limitations on the weight of the machine as well as upon its size, such as will permit its being handled with accuracy and with a minimum of physical exertion, and at the same time necessitates provision for adequate power requirements and a high cutting or abrading rate. The proper cooling of the motor and the abrading element, and the convenient disposal of dust also are factors of great importance in the utility of the machine.

Included among the more particular objects of the invention, therefore, are the following:

The provision of a construction wherein all working parts are effectively housed and protected from interference from the clothing or the person of the operator or other external articles;

Improved organization of the machine for facilitating adjustment of the operating drum relative to the work during operation;

Improved organization of the drum mounting and driving mechanism, permitting adjustment of the drum for alignment of its operating surface with the work, when desired;

A novel mounting arrangement for the machine whereby it may be operated conveniently and accurately for floor smoothing,

with the working pressure constantly under the control of the operator.

Other and further objects of the invention will be pointed out hereinafter, indicated in the appended claims, or obvious to one skilled in the art upon an understanding of the invention from the present disclosure.

For the purpose of this application, I have shown herein one form of apparatus embodying the invention, but it is to be understood that the same is presented for illustration only and is not to be accorded any interpretation having the effect of limiting the invention set out in the appended claims, short of its true and most comprehensive scope in the art.

In the drawings forming a part of this specification,

Fig. 1 is a top view of a sanding machine without the dust sack;

Fig. 2 is a left hand side elevational view;

Fig. 3 is a sectional view on substantially line 3—3 of Fig. 2, showing most of the casing portion of the machine in elevation;

Fig. 4 is a longitudinal sectional view on substantially line 4—4 of Figs. 1 and 3;

Fig. 5 is a transverse sectional view on substantially line 5—5 of Fig. 2;

Fig. 6 is a longitudinal sectional view on substantially line 6—6 of Fig. 1;

Fig. 7 is an elevational detail taken at the point indicated at 7—7 on Fig. 5;

Fig. 8 is a sectional plan view on the line 8—8, Fig. 7;

Fig. 9 is a top view showing the machine mounted for floor work, and

Fig. 10 is a side elevational view of the same.

Described generally, my invention comprises the novel organization of an operating drum, suitable for carrying sandpaper or other desired surfacing material, and a motor for actuating the drum, said parts being suitably housed in a casing adapted to present the working parts in proper relationship to the

surface to be acted upon by the surfacing material. A characterizing feature of the construction is the organization of the parts in such fashion that the complete operative machine is of such limited size and weight as to permit its being utilized with accuracy and without inappropriate exertion on the part of the operator, as a hand-tool for bench work. Novel features in the organization which accomplish this result involve the provision of an operating drum of small diameter and a high speed motor operably connected with the drum in such fashion as to drive the same with a peripheral speed, preferably 3170 linear feet per minute under average working conditions. Instead of relying on the weight or pressure or extensive contact between the abrading material and the work, to secure the desired cutting or abrading effect on the latter, my invention contemplates a relatively small area of contact, very limited pressure, and a relatively high rate of movement of the abrading element. In these features it differs fundamentally from the construction of wood sanding machines heretofore most extensively in use.

The invention will be understood more in detail by reference to the accompanying drawings. In the form herein illustrated, let it be understood that the reference numeral 10 designates a base frame, the lower portion of which is formed as a plane surface adapted to rest and travel upon the work, forming a support for the operating mechanism and a guide for the abrading element in its action on the work. This base is transversely slotted at 11 to provide an aperture in which the abrading element operates. The base member includes the upstanding lateral flanges 12 and the transverse reinforcing flanges 14, in association with certain of which are formed the bosses 15 for attachment of the carriage, in the manner hereinafter described. The base member also is formed with the upstanding lugs 16 which constitute the mountings for the casing, and a lug 17 to which is pivotally connected the casing adjusting screw 18. The casing, which has hinged connection with the base frame 10 by means of its hinge lugs 19 and pintles 20, is subdivided into a number of housings for the various operating parts. Its lower part 21 forms a housing for the drum, said housing being open at the bottom in a position over the base slot 11. An articulate partition 22 separates the drum housing from the motor housing 24, which is positioned above the drum housing, and has an open side, in which is mounted the motor frame plate 25. At the front of the drum housing is formed the suction duct 26, having its inlet 26^a at the lower edge of the casing. This duct extends up over the front of the drum housing in the form shown in Fig. 3, with a gradual change from the slot-

like dimensions of the inlet to a narrower and deeper form of conduit, which turns laterally at 26^b and then continues upwardly at 26^c, partly across the end of the motor housing where it terminates in a port 26^d communicating with a fan compartment 27. The outer side of the fan compartment is closed by the gear housing 28, which is fitted at its outer side with a cover plate 29. At its front side, the fan housing is provided with the dust outlet 27^a. At the middle of the front and rear sides of the casing are provided the handle seats 30 in which are mounted the handle yokes 31. In one of the yokes is mounted the handle 32 having the switch housing 34 formed at the upper end thereof and enclosing a switch which is operated by the lever 35 to control the supply of current through the cable 36. In the other handle yoke is rotatably mounted the adjusting handle 37, the lower portion of which is formed for screw-thread engagement with the adjusting screw 18. By rotation of the handle 37, therefore, the casing may be swung on the pintles 20 to vary the elevation of the parts carried in the casing relative to the base. A flexible apron 38 is attached to the front of the casing, extending across the same and bearing at its lower edge on the upper surface of the base, 95 said apron accommodating the adjustment of the casing.

Bushings 39 and 40 are mounted in the side walls of the drum housing and carry the drum arbor 41, on which are supported the roller bearings 42, which carry the drum 44. The drum is a hollow cylindrical member, slightly chamfered at its ends, and having the end flanges 44^a which carry the hub portions 45 in which the roller bearings are mounted. A tube 46 is supported between the hub portions as a lubricant housing for the bearings 42, which tube prevents access of dust to the bearings from the inside of the drum, while they are similarly protected at the outside by the packing gaskets 47. The drum is provided with a diagonal groove 47^a in its face, in which is mounted a clamping strip 48 which may be drawn up by screws 48^a that interanchor bushings 48^b having screw-threaded engagement with bosses 48^c in the drum 44, whereby to clamp the sandpaper on the periphery of the drum. A pinion 49 having spiral teeth is secured coaxially to one of the hub members 45. The mounting of the arbor 41 in the bushing 40 is eccentric of the latter, and the bushing may be rotated in its mounting in the casing wall by means of a spanner engaged in the spanner holes 40^a. In this fashion the adjacent end of the drum may be raised and lowered so as to obtain the desired bearing of the sandpaper against the work throughout the length of the drum. The screws 40^b retain the bushing 40 in the 130

desired adjustment. The periphery of the drum is covered with a layer of compressible material 50, such as felt, upon which the sandpaper 51 is tightly constricted by the clamping strip 48.

5 Within the motor housing 24 are mounted the field elements 52 and commutator brushes 54 of a high speed motor of the universal type, the armature 55 and commutator 56 of which are carried on the rotor shaft 57. This shaft is carried at one end in the ball-bearing 58 supported in the cover plate 25, and at the other end in the bearing 59 carried in the gear housing 28, and extends through the air duct 26^a and the fan housing 27. In the latter is the centrifugal fan 60, mounted on the armature shaft 57. The fan housing and exhaust duct 26^a have communication with the motor housing through the opening 54^a in 10 the side wall of the latter. On the end of the armature shaft, and housed by the gear casing 28 and cover plate 29, is a spiral-tooth pinion 61 which meshes with a similar pinion 62 that is carried on the bearing 64 mounted on 15 a stud 65 in the gear casing 28. The pinion 62 meshes with a spiral-tooth pinion 66 which is fixed to a short counter-shaft 67 one end of which is journalled in a ball-bearing 68 carried by the gear case cover 29. The other end 20 of said shaft 67 is journalled in a ball-bearing 69 supported in the gear casing. The last mentioned bearing is of double-row construction and takes up the thrust both endwise and radial, imposed on the shaft 67. At its inner 25 end the stub shaft 67 carries the pinion 70 which meshes with the pinion 49 secured to the drum. Through this chain of gearing the drum is driven by the motor in a direction which is clockwise when viewed in the position illustrated in Figs. 4 and 6, in which 30 operation, it will be observed the dust is thrown from the sandpaper toward the apron 38 and intake 26^a of the exhaust duct which is close to the periphery of the drum where it 35 leaves the work.

The motor is of the series-wound universal type designed to be employed with either alternating or direct current, and to develop approximately one-half horsepower. The 40 drum 44 is of relatively small diameter, so as to permit the sandpaper to have only a very limited degree of contact with the work. For example, with a drum having a diameter of approximately four and one quarter inches 45 the extent of peripheral contact of the sandpaper with the work will be only about $\frac{1}{16}$ to $\frac{3}{32}$ of an inch under working conditions. At a drum length of about one and one half of the drum diameter and the usual weight of 50 such tools of less than 50 pounds the sanding drum will be applied against the treated surface with a pressure of less than nine pounds per inch of cutting length, the pressure being in general of the order of about $4\frac{1}{2}$ pounds 60 per inch cutting length. With these charac-

teristics of the motor, drum and driving connections, the drum will be driven at a speed of approximately 2850 R. P. M., with a peripheral speed of approximately 3170 feet per minute under the average working conditions, the motor being energized from the usual lighting circuit carrying a constant pressure of approximately 110 volts. As stated, this represents the average working condition, these working conditions being 70 variable, due principally to the variations in the character of the sandpaper. When the sandpaper is new and sharp it will cut more readily than when old and worn and hence, due to the characteristics of the motor, the 75 drum speed will be somewhat below the average rate, to a possible extent of 15%. When the paper is old and worn, or if it is of particularly fine grain, it will encounter less resistance from the work, with the result that 80 the drum speed may be increased as much as possibly 15% above the average. The characteristics of the apparatus under all working conditions, however, are the actuation of the drum at a relatively high speed with the 85 abrading element having a relatively small degree of contact with the work under a comparatively light pressure. The degree of contact is limited by the relatively small diameter of the drum and the pressure by the 90 lightness of the entire device. The speed characteristic of the motor, in its variation inversely with respect to the resistance between the work and the drum, acts as a safeguard against the scorching of the wood by 95 the heat of friction. When the sandpaper is sharp and the resistance offered by the wood consequently not great, the drum will be actuated at a speed somewhat below the average without the development of frictional heat 100 in an amount dangerous to the wood. As the sandpaper becomes worn, and although there is actually more surface rubbing of the wood, the resistance to the drum is thereby decreased, and the speed of the drum, because 105 of the characteristics of the motor, will be increased above the average.

The high speed motor permits the operation of the fan with direct connection to the armature shaft, the fan inducing a very strong and sustained exhaust suction through the exhaust duct, which is effective to handle all of the dust produced by the abrading element. This leaves the abraded surface of the 115 work perfectly clear of dust so that its condition may be minutely inspected, and it keeps the working parts clear of dust so that there is no danger of their being clogged or disabled from that source. It also prevents the dust circulating to the operator and surrounding workers. The action of the fan induces a sustained current of air through the motor housing, the air finding admission through a series of holes 25^a in the plate 25 at one side of the motor, and thence through 120 125 130

the aperture 54^a into the portion 26^a of the suction duct 26. A suitable dust bag 74 is arranged to be attached to the mouth of the discharge conduit 27^a for reception of the dust from the fan housing.

- 5 While the device is adapted particularly for bench work, it is capable of use as a floor sanding machine by means of a carriage device which is illustrated in Figs. 9 and 10.
- 10 This carriage device comprises a frame portion 75 fitted with the angularly extending handle 76, of suitable length, and having the depending lugs 77 in which are mounted a rod 78 forming journals for wheels 79. The frame 75 is adapted for removable connection to the bosses 15 of the base by means of the screws 80, forming a rigid connection between those members. The length of the lugs 77 and size of the wheels 79 are such that
- 15 20 when the carriage is so connected to the base, the adjacent end of the latter will be held slightly above a surface on which the wheels rest. By suitable adjustment of the casing on the base, therefore, the drum may be so positioned that the device will be supported on the drum and the wheels 79. By means of the handle 76 the operator may manipulate the device from a standing position for floor sanding. In this manipulation, the pressure
- 25 30 of the abrading element upon the floor is constantly under control of the operator, which is exercised by his supporting more or less of the weight of the machine through the leverage of the handle 76. The wheels 79 afford a fulcrum support whereon the machine may be lifted by the depression of the upper end of the handle. The wheels 79 rotate independently, so that the machine may be very easily guided. It will be observed that
- 35 40 the pull of the drum 44 is away from the handle 76, which is an important factor in facilitating control and guidance of the device in its operation on the floor surface.

A machine embodying my invention possesses many features of superior efficiency. In the first place, by the employment of the principles which characterize my invention, the machine may be built in very small size and with very light weight, both of which characteristics are essential in a bench machine. The organization of the apparatus in such fashion that the abrading element is driven at a high speed produces a very rapid cutting, which is rendered practicable by the limitation of the pressure on the abrading element, and the limitation of the extent of travel of the abrading element in contact with the work which is accomplished by the use of a drum of relative small diameter. As pointed out above, the characteristics of the motor co-operate in attaining this efficient performance through its compensating response to increased resistance of the work to the abrading element, whereby a definite limitation is imposed on the development of frictional heat.

The suction at the inlet of the exhaust duct induces a strong current of air across the abrading surface, thus exercising a cooling effect on the latter. The employment of a motor of these characteristics, in addition to the effect just mentioned, permits the weight of the machine to be kept low and adapt it for universal use on lighting circuits without requiring the insertion of special fuse connections ahead of it. Another economy is effected in the use of sandpaper by the employment of a small diameter drum and a high speed operation with low pressure, as a considerably greater surface area may be sanded with a materially less area of sandpaper and in substantially less time than with machines operating at the usual slower speeds with heavier pressure of the abrading material on the work.

I claim:

1. A wood surfacing machine comprising a base portion, a casing adjustably mounted on the base portion, and an abrading drum operably mounted in the casing, an apron mounted on the casing and having adjustable engagement with the base member in front of the drum, an exhaust duct formed on the casing and having its inlet between the drum and the apron above the base member, a fan operably mounted in the casing in communication with the exhaust duct, and a motor housed in the casing for driving the fan and drum.

2. In a wood surfacing machine, in combination, a base member, a casing adjustably mounted on the base member for movement toward and from the same, an abrading drum operably mounted in the casing and adjustably therewith relative to the base member, an adjustable apron extending from the casing to the base member in front of the drum, and an air duct formed on the casing with its inlet between the apron and the drum.

3. In a wood surfacing machine, in combination, a base member, a casing mounted thereon, an abrading drum mounted in the casing, means on said base for vertically adjusting the height of said casing, said casing having a driving connection at one end of the drum for rotating the same, and an adjustable mounting at the other end of the drum for varying its inclination with respect to the base member.

4. In a wood surfacing machine, in combination, a casing, an abrading drum operably mounted therein, an exhaust duct formed on the casing for induction of air near the drum, said casing formed with a motor housing portion and a fan housing portion, both in communication with the exhaust duct, a fan in the fan housing, and a motor in the motor housing for inducing a current of air through the motor housing and exhaust duct.

5. A surface smoothing machine whose entire effective weight does not exceed fifty

5 pounds, comprising a frame for support on the surface to be treated, an abrading drum having a diameter of approximately 4½ inches mounted in the frame for peripheral engagement with the treated surface, and a motor mounted on the frame and having driving connection with the drum, said motor being modified against standard practice so that when the drum is pressed against the 10 working surface by the weight of the associated structure the drum will be driven at a peripheral speed approximating 3000 feet per minute.

6. In a surface smoothing machine whose 15 entire weight does not exceed fifty pounds, the combination of a frame for support on the surface to be treated, a sanding drum of small diameter of about six inches or less operably mounted on the frame for peripheral contact 20 with the treated surface, and a motor operably mounted on the frame and having driving connection with the drum, said motor being modified against standard practice so that when the drum is pressed against the 25 working surface by the weight of the associated structure the drum will be driven at a peripheral speed of approximately 3000 feet per minute.

7. In combination with a surfacing machine, comprising an abrading drum, a driving motor therefor, and a frame carrying said drum and motor, of a carriage including a member mounted in overlapped relation to the machine frame, an outwardly extending handle, means for attaching and holding the carriage in its overlapped relation to the machine frame, and a support depending from the carriage for sustaining the adjacent portion of the machine frame 40 in elevated relation to the surface to be treated.

8. In combination with a surfacing machine, comprising a frame, an abrading drum carried thereby, and means for actuating said 45 drum, of a carriage including a bracket mounted in overlapped relation to the machine frame, an outwardly extending handle associated with the carriage, means for attaching and holding the bracket in its overlapped relation to the machine frame, depending lugs supported by the carriage for sustaining the adjacent portion of the machine frame in elevated relation to the surface to be treated, and rollers mounted on 50 said depending lugs for contact with said surface.

9. In combination with a surfacing machine comprising a frame, provided with a plurality of upstanding lugs, an abrading 60 drum carried by said frame, and means for actuating said drum, of a carriage including a bracket mounted in overlapped relation to the machine frame, and extending over said upstanding lugs, an outwardly extending 65 handle associated with the carriage, fastening

devices engaging the said lugs, and serving to attach and hold the carriage bracket in its overlapped relation to the machine frame and supporting means depending from the carriage for sustaining the adjacent portion of the machine frame in elevated relation to the surface to be treated. 70

10. In a wood surfacing machine, the combination with a rotary cutting drum, a rotary motor having a driving shaft, an exhaust fan connected to one end of said shaft, and gearing between said shaft and drum for rotating the same, of a unitary casing having partitions forming therein a compartment enclosing said drum, a compartment enclosing said motor and said fan, and a compartment enclosing said gearing, said drum compartment having an opening at the bottom thereof to expose a portion of said drum to the working surface, and an exhaust duct 80 connecting said drum compartment with the exhaust space of said fan. 85

11. In a wood surfacing machine, the combination with a rotary cutting drum, a rotary motor having a driving shaft, an exhaust fan connected to one end of said shaft, and gearing between said shaft and drum for rotating the same, of a unitary casing having partitions forming therein a compartment enclosing said drum, a compartment enclosing said motor and said fan, a compartment enclosing said gearing, said drum compartment having an opening at the bottom thereof to expose a portion of said drum to the working surface, and an exhaust duct connecting said 90 drum compartment with the exhaust space of said fan, said exhaust duct being formed on the surface of said casing and having a common wall therewith. 95

12. In a wood surfacing machine, the combination with a rotary drum having a cylindrical cutting surface, a rotary driving motor having a shaft extending parallel to said drum, an exhaust fan on said shaft, and gearing connecting said shaft with one end of said drum to rotate the latter, of a unitary casing having partitions separating the same into a compartment surrounding said motor, a compartment surrounding said fan, a compartment surrounding said drum, and a compartment surrounding said gearing, said drum compartment having an opening for exposing a portion of said drum toward the working surface, said fan compartment having a central intake chamber communicating with said motor compartment for drawing cooling air therethrough, and an exhaust duct extending between said drum compartment and said intake chamber, said exhaust duct having an elongated intake nozzle along said drum. 110 115 120

13. In a wood surfacing machine, the combination of a drum having a cylindrical cutting surface, a rotary motor having a driving shaft, a fan disposed on one end of said shaft, said fan being arranged to exhaust air in the 125 130

direction from the center to the periphery thereof and having a central intake space directed toward said motor, a unitary casing having partitions separating the same into a compartment surrounding said motor, a compartment surrounding said fan, and a compartment surrounding said drum, said drum compartment having an opening for exposing a portion of said drum, said fan compartment having a central intake chamber of reduced diameter extending between said fan and said motor, and an exhaust duct connecting said drum compartment with said intake chamber.

14. In a wood surfacing machine, the combination of a drum having a cylindrical cutting surface, a rotary motor having a driving shaft, a fan disposed on one end of said shaft, said fan being arranged to exhaust air in the direction from the center to the periphery thereof and having a central intake directed toward said motor, a unitary casing having partitions separating the same into a compartment surrounding said motor, a compartment surrounding said fan, and a compartment surrounding said drum, said drum compartment having an opening for exposing a portion of said drum, said fan compartment having a central intake chamber of reduced diameter extending between said fan and said motor, and an exhaust duct connecting said drum compartment with said intake chamber, said exhaust duct being formed on the walls of said casing and having common wall portions therewith.

15. In a wood surfacing machine, the combination of a drum having a cylindrical cutting surface, a rotary electric motor having a central driving shaft, a fan mounted on said shaft, gearing connecting said shaft with said drum to rotate the latter, a unitary casing having partitions forming a compartment surrounding said drum and a compartment enclosing said motor, a removable cover on one end of said motor compartment, said cover having a hollow chamber, the gear driving end of said motor shaft extending through said cover wall and terminating in said hollow chamber, the gearing connecting said driving end with said drum being housed and supported in said hollow chamber, and an exhaust duct extending between said drum compartment and the exhaust portion of the compartment surrounding said fan.

16. A wood surfacing machine comprising a drum having a cylindrical cutting surface, an electrical driving motor having a central driving shaft extending parallel to said drum, a unitary casing constituting a substantially cylindrical chamber surrounding said motor, and a chamber surrounding said drum, said drum chamber being open at its bottom for exposing a portion of said drum towards the working surface, said drum chamber and said motor chamber having common wall portions

and a removable cover for enclosing the driving end of said motor chamber, said cover having a hollow chamber extending transversely to said shaft in the direction toward said drum, said shaft terminating within said chamber, and gearing disposed in said chamber for connecting said shaft with said drum, said gearing comprising supporting shafts journaled in the walls of said chamber. 70

17. A wood surfacing machine comprising 75 a drum having a cylindrical cutting surface, a casing having a chamber enclosing said drum, said chamber having an opening at the bottom thereof for exposing a portion of the drum against the working surface, a base plate 80 for guiding said casing with said drum on said working surface, said base plate having a slot for exposing said drum to the working surface, means for vertically adjusting said casing on said base plate to vary the degree of exposure of the drum through said slot, and an exhaust duct for removing waste particles incident to the cutting operation of said drum, said exhaust duct having an inlet nozzle adjacent said drum above said slot, the space between the bottom opening of said casing and said slot having an enclosure for confining the suction air current to the portion of the drum near said slot while permitting vertical adjustment of said casing. 85 90 95

18. A wood surfacing machine comprising a drum having a cylindrical cutting surface, an electric motor having a driving shaft, a unitary casing for said drum and motor having partitions forming therein a chamber 100 enclosing said drum, said chamber having a slot at the bottom thereof for partially exposing said drum, and a chamber surrounding said motor and said fan, a base plate for supporting said casing and guiding the same on a working surface, said base plate having a slot through which the exposed portion of the drum may be projected toward the work, means for varying the depth of the projecting portion of the drum extending through said 105 slot, and an exhaust duct extending from said fan for sucking away waste particles produced by the cutting operation of said drum, said duct having an inlet member adjacent the slot in said base plate and arranged to adjustably confine the suction air current to the portion of the drum near said slot throughout the range of adjustment of the position of said drum with respect to said base. 110 115

19. A wood surfacing machine comprising 120 a drum having a cylindrical cutting surface, an electric motor having a driving shaft, a unitary casing for said drum and motor having partitions forming therein a chamber enclosing said drum, said chamber having a slot 125 at the bottom thereof for partially exposing said drum, and a chamber surrounding said motor and said fan, a base plate for supporting said casing and guiding the same on a working surface, said base plate having a slot 130

- through which the exposed portion of the drum may be projected toward the work, a pivotal connection between said casing and said base on one side of said drum to permit 5 tilting of the casing for varying the depth of the projecting portion of the drum extending through said slot, an exhaust duct extending from said fan for sucking away waste particles produced by the cutting portion of said drum, 10 said duct having an inlet nozzle adjacent the slot on the side opposite said pivotal connection, and means for confining the suction air current to the portion of the drum near said slot throughout the range of the pivotal movement of said casing with respect to said base. 15
20. The combination with an independently operable wood surfacing machine of the bench type comprising a base plate having a slot, a casing supported on said base plate, 20 said casing having a cutting drum chamber and a motor chamber, a cutting drum mounted in said drum chamber and having an exposed portion projecting through said slot toward the work, and a driving motor for said drum 25 mounted in said motor chamber, of a detachable carriage for adapting said machine for floor operation comprising a bracket overlapping said base plate and engageable therewith, roller means depending from said 30 bracket and extending below the base of said base plate, and a handle extending upwardly back of said roller means whereby said roller means forms a fulcrum whereon said drum 35 may be elevated by depression of said handle.
35. 21. In a wood surfacing machine, the combination with an independently operable cutting unit comprising a drum having a cylindrical cutting surface, a rotary motor for driving said drum, and a casing for operably 40 mounting said drum and said motor, said drum being so associated in said casing as to expose a portion of said drum against the working surface and guide said drum thereon, of a detachable carriage having a bracket 45 member for engagement with said casing, means for detachably securing said bracket member to said casing, roller means depending from said bracket to engage the working surface for permitting said drum to be pivotally 50 swung around said roller means toward and from said working surface, and an upwardly projecting handle extending from said bracket for guiding said carriage and swinging said casing thereon.
55. 22. A wood surfacing machine comprising a drum having a cylindrical cutting surface, an electric motor for rotating said drum, a casing having partitions therein forming a compartment surrounding said motor and a 60 compartment surrounding said drum, said drum compartment having an opening at the bottom thereof for exposing a portion thereof toward the working surface, a base plate for guiding said casing and said drum, said 65 base having a slot, a pivotal connection be-
- tween said casing and said base on one side of said drum to permit said drum to be swung toward and away from said slot for projecting more or less of said drum toward said working surface, fan means driven by said 70 motor for producing a suction air current to remove waste particles incident to the cutting operation of said drum, and a suction duct leading from said fan means, said suction duct having an inlet nozzle extending into the 75 space between said drum and said base on the side opposite said pivotal connection.
23. In a wood surfacing machine, the combination with an abrading drum, a rotary motor, a driving connection between said 80 drum and said motor for rotating the drum, and an exhaust fan driven by said motor, of a unitary one-piece casing having two tubular chambers, the axes of said chambers being substantially parallel, one of said chambers 85 having mounted therein said operating drum in a direction parallel to its axis, the other of said chambers having mounted therein said rotary motor with its axis substantially parallel to the axis of said drum, said drum compartment 90 having an opening for exposing a portion of the periphery of said drum to the work surface, the walls of said casing being double over a portion thereof and forming a duct communicating at one end with said drum chamber 95 and at the other end with the exhaust space of the fan in said motor chamber.
24. In a wood surfacing machine, the combination with an abrading drum, a rotary motor, a driving connection between said drum and said motor for rotating said drum, and an exhaust fan driven by said motor, of a unitary one-piece casing having a compartment 100 for housing said drum, a compartment for housing said motor and a compartment for 105 housing said exhaust fan, said casing being at least in part double walled, the space between said double walls forming a duct one end of which communicates with said drum compartment and the other end of which communicates with the exhaust space of said fan to 110 constitute an exhaust duct for removing waste particles produced by the action of said drum.
25. The method of operating a surface smoothing machine having a motor driven abrading drum which consists in rotating said drum at a peripheral speed approximating 3000 feet per minute while pressing said drum against the treated surface with a pressure of less than nine pounds per inch of drum length. 115
26. The method of operating a wood surfacing machine having a sanding drum of a diameter of about six inches or less which consists in utilizing the weight of said machine for applying to said drum the pressure of the order of five pounds per inch drum length while rotating said drum at the peripheral speed of approximately 3000 feet per minute. 125
27. A surfacing machine comprising a sanding drum of a diameter of about six 130

inches or less, a support for said machine for guiding the same over the surface to be treated, a motor mounted on said support and having a driving connection with said drum, the total weight of said machine being such that said drum is applied against the surface to be treated with a pressure of less than nine pounds per inch drum length, said motor being arranged to drive said drum under said pressure against the treated surface at a peripheral speed of the order of 3000 feet per minute.

In testimony whereof I have hereunto subscribed my name.
